UNITED STATES PATENT OFFICE.

ANTHONY PEGORIK, OF OXFORD JUNCTION, IOWA.

PUMP ATTACHMENT.

Application filed November 13, 1924. Serial No. 749,736.

To all whom it may concern:

Be it known that I, ANTHONY PEGORIK, a citizen of the United States, residing at Oxford Junction, in the county of Jones and 5 State of Iowa, have invented a new and useful Pump Attachment, of which the following is a specification.

This invention relates to pump attachments and aims to provide novel means 10 which may be supported adjacent to a pump cylinder to prevent the cylinder from becoming disconnected from the tubing and falling into the well.

An important object of the invention is 15 to provide a device of this character which may be readily and easily positioned on well tubing at little expense.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

30 Figure 1 is an elevational view disclosing well tubing and a cylinder connected therewith, the device forming the subject matter of the invention being shown as positioned therein.

35 Figure 2 is a fragmental elevational view showing one of the arms of the attachment.

Figure 3 is a sectional view taken on line 3-3 of Figure 1.

Referring to the drawing in detail, the 40 device includes a pair of arms 5 which are formed with inwardly extended end por-

tions 6 that are slightly twisted as at 7 to provide relatively flat extremities.

Openings are formed in the extremities 45 of the arms 5 and accomodate the bolts 8 which also pass through suitable openings in the ends of the pipe embracing members 9 which closely engage the pipe sections 10 to which the pump cylinder, which is indicated at 11, is secured.

Nuts 12 are positioned on the bolts 8 and 50 secure the pipe embracing members 9 and arms 5 together, the arms 5 having their ends positioned between the ends of the pipe embracing members 9 as at 13.

55 From the foregoing it will be obvious that should the cylinder 11 become accidentally disconnected from the heads disposed at the ends thereof, or should the heads become disconnected from the pipes shown 60 as extending thereinto, the pipe embracing members 9 would move into engagement with the heads of the cylinder 11 to support the pipe sections and prevent the lower section from falling into the well.

65 I claim:—

A guard for attachment to pump tubing adjacent to the cylinder secured thereto, said guard comprising arms having offset end portions adapted to lie adjacent to the 70 tapered ends of a cylinder, and semi-circular connecting members adapted to embrace portions of the pipes adjacent to the cylinder for securing the guard in position.

75 In testimony that I claim the foregoing as my own, I have hereto affixed my signature in the presence of two witnesses.

ANTHONY PEGORIK.

Witnesses:

JOHN BURESH,
JOE A. LENFELD.
